US0D1024997S

(12) **United States Design Patent** (10) Patent No.: **US D1,024,997 S**
(45) Date of Patent: ** Apr. 30, 2024

(54) **MULTIMEDIA AMPLIFIED SPEAKERS**

(71) Applicant: **Shenzhen Mushi Electric Appliance Co., Ltd.**, Shenzhen (CN)

(72) Inventor: **Guomin Huang**, Shenzhen (CN)

(73) Assignee: **Shenzhen Mushi Electric Appliance Co., Ltd.**, Shenzhen (CN)

(**) Term: **15 Years**

(21) Appl. No.: **29/775,536**

(22) Filed: **Mar. 24, 2021**

(51) LOC (14) Cl. **14-01**

(52) U.S. Cl.

USPC **D14/204**

(58) **Field of Classification Search**

USPC D14/168, 170, 171, 203.1, 204, 209.1,

D14/210, 211, 214, 215, 221
